UNITED STATES PATENT OFFICE

1,957,931

AIRPLANE TAKE-OFF ACCELERATOR

Charles A. R. Benedict, Edwardsville, Ill.

Application April 2, 1930, Serial No. 441,097

1 Claim. (Cl. 244—2)

The invention has for its object to provide a device enabling airplanes to take-off from a restricted area.

Fig. 1 is an elevational view of my apparatus attached to a portion of an airplane.

Figs. 2, 3 and 4 are similar views or modifications of the same apparatus.

In all the figures "A" is the frame, "B" is the blade, "C" is the tail skid, "d" is the pivot on which the blade moves, "e" is the rope holding the plane to a stationary object, "f" is the cutting edge of the apparatus, "g" is the groove in which the rope rests when ready for operation, "h" is the cable extending from the apparatus to a point in the cabin near the pilot. In Figure 4

"s" is the spring which moves the blade when released by the trigger "j"; all other parts are lettered as in Figures 1, 2 and 3.

I claim:

A device for releasing an airplane secured to a fixed object by a rope, comprising a member secured to a rear part of the airplane, having a notch therein for receiving a bight of said rope, a knife device secured to said member but movable across said notch to cut the rope, a control means extending from said knife device to a location adjacent to the pilot's position in the airplane whereby the knife may be moved across the notch. 60
